UNITED STATES PATENT OFFICE.

JOHN W. COVINGTON, OF SALT LAKE CITY, UTAH.

CONVERTIBLE DAY COACH AND SLEEPER.

1,417,719.

Specification of Letters Patent.

Patented May 30, 1922.

Application filed August 6, 1918. Serial No. 242,593.

To all whom it may concern:

Be it known that I, JOHN W. COVINGTON, a citizen of the United States, residing at Salt Lake City, in the county of Salt Lake and State of Utah, have invented certain new and useful Improvements in Convertible Day Coaches and Sleepers, of which the following is a specification, reference being had therein to the accompanying drawing.

10 This invention relates to mechanism, whereby a day coach may be easily and quickly converted into a sleeping car, thereby utilizing a greater amount of space than is possible in the regulation sleeping cars, 15 and permitting the adaptation and utilization of the many thousands of day coaches for night runs.

The main object of the present invention is the provision of a simple, durable and inexpensive mechanism, where tiers of two beds or cots may be properly mounted to be carried adjacent the ceiling of the car when not in use, but which can be quickly lowered to present a series of upper and 25 lower berths upon each side of the car throughout the length thereof.

In the accompanying drawings:—

Figure 1 is a cross section through one side of a day coach, showing the present 30 mechanism in end elevation, full lines showing the berths lowered into position for use, and dotted lines showing them out of use.

Figure 2 is an enlarged detail view partly in section of the berth controlling windlass.

35 Figure 3 is a top view of one of the sliding supports for a berth, and

Figure 4 is a similar view of another form.

Referring to the drawings, A designates 40 the roof, B the inner face of the wall, and C the outer face of the wall of a day coach. The seat D is of usual construction, provided with the supporting aisle leg G, mounted upon the floor I of the car, and 45 which carries the seat frame E, and the handle or arm F.

The present berth mechanism consists of the inner supporting members 18, two to each pair of berths 1 and 2, and these 50 members 18 are made from tubular metal rods, with the attaching members 19 bolted to the side wall of the car. Carried by the two rear corners of the upper berth frame 1 are the rod engaging plates 3, each of 55 which is constructed as clearly shown in Figure 3, being riveted to the angle mem-

bers 13 and 26, and being provided with an opening a which slidably fits upon the support 18, so that the upper berth may assume either full or dotted line positions of Figure 60 1. The lower berth 2 is provided with the rod engaging plate 4, Figure 4, which is provided with the opening b, which is shaped to permit the plate 4 to pass the two lower attaching members 19, to permit the 65 lower berth 2 to assume the full and dotted line positions of Figure 1.

The berth 2 is provided with a folding leg 14 upon the aisle side, and where the seat backs are removable, the lower berth is 70 made to assume a position 27½ inches above the floor.

To raise and lower the berths the cables 12 and 23 are provided, the former being attached to the plate 4 and passed through 75 and opening in the plate 3 of the upper berth, and about the guide pulley 20 attached to the upper end of the support 18, to be wound upon or released from the reduced diameter portion 6 of the control- 80 windlass 7, which is mounted fixedly upon the longitudinal shaft 17, mounted in the brackets 16, connected as at 15 to the ceiling or roof A. The cable 23 is attached to be wound upon or released from 85 the enlarged portion 5 of the windlass 7. There are two pairs of cables and two windlasses 7 to each two berths, but the cable 23 in no way controls the upper berth 1, whose aisle end is supported by the chains 28, one 90 being here shown, attached at their upper ends to the brackets 16.

Attached fixedly to the shaft 17, is a gear 8, driven by the worm 9, which in turn is operated by the rod or shaft 10, carrying 95 the operating hand wheel 11.

It will thus be seen that by revolving the shaft 17, the lower berth 2 will be first elevated and will finally raise the upper berth, and due to the fact that the double diameter windlasses 7 are employed the aisle side of the lower berth will be raised more rapidly to permit the berths to assume the dotted line position of Figure 1.

It is also possible to make the lower 105 berths and the upper berths the full length of the car, so that when the shaft 17 is operated the complete set on each side of car is moved to the desired position for receiving the beds.

For ambulance cars, a knock down frame is built with tracks on the aisle side to per-

mit the slipping of the beds into position, such beds being supplied with rollers, so that the patient and bed can be easily carried about.

5 By the use of this device, a day coach can be easily converted into a sleeper and due to this arrangement an ordinary car can be made to accommodate from 108 to 180 men, making this arrangement especially desirable for the transport of troops.

10 What I claim, as new, is:—

15 1. The combination with a supporting structure, of a berth mechanism, including vertical supports, a plurality of berth frames, means for slidably connecting the rear edges thereof to the vertical supports, and a raising and lowering mechanism, for moving the berths simultaneously into and out of operative position the movement of the aisle 20 edges being more rapid than the rear edges.

25 2. The combination with a day coach, of a mechanism for converting the same into a sleeper, including a plurality of vertical supports connected to each side of the coach, a plurality of superposed berth frames having their rear edges slidably and tiltably mounted upon the vertical supports, a shaft mounted longitudinally of the coach adjacent the roof thereof, means for rotating the 30 shaft, and means connected to the shaft and frames whereby the aisle ends of the frames are supported and the frames are raised or lowered by revolving the shaft.

35 3. The combination with a day coach, of a mechanism for converting the same into a sleeper, including a plurality of vertical supports attached to each side wall of the car, two berth frames having their wall edges

slidably and tiltably connected to the vertical supports, said berth frames being superposed, 40 two pairs of cables attached to the lower berth frame, a shaft mounted longitudinally of the coach, means for rotating said shaft, and two double diameterd windlasses fast to said shaft for engaging said cables to cause 45 the aisle ends of the berth frames to move more rapidly than the rear ends when said berth frames are being raised or lowered.

4. The combination with a supporting structure, of a bed mechanism including a 50 plurality of parallel supports mounted within the structure, a plurality of superposed berth frames having their rear ends slidably and tiltably mounted upon the supports, a shaft mounted longitudinally of the 55 supporting structure, means for rotating the shaft, and means connected to the shaft and to the berth frames, whereby the berth frames are moved slidably upon the vertical support and the free ends are supported. 60

5. The combination with a supporting structure, of a bed mechanism including a plurality of parallel supports mounted within the structure, a plurality of superposed berth frames having their rear ends slidably 65 mounted upon the supports, a shaft mounted longitudinally of the supporting structure, means for rotating the shaft, and means connected to the shaft and to the berth frames, whereby the berth frames are moved slidably 70 upon the vertical support, the aisle edges of the berth frames being adapted to be moved more rapidly during the ascent or descent than the edges connected to the supports.

In testimony whereof I affix my signature. 75
JOHN W. COVINGTON.
